UNITED STATES PATENT OFFICE.

JOHN F. WHITE, OF KARNES CITY, TEXAS.

HAY-PRESS.

1,296,889.

Specification of Letters Patent. Patented Mar. 11, 1919.

Application filed August 9, 1918. Serial No. 249,149.

To all whom it may concern:

Be it known that I, JOHN F. WHITE, a citizen of the United States, residing at Karnes City, in the county of Karnes and 5 State of Texas, have invented new and useful Improvements in Hay-Presses, of which the following is a specification.

This invention relates to new and useful improvements in baling presses and the 10 principal object of the invention is to provide simple and efficient means for operating the press and to improve the construction of the press itself.

Another object of the invention is to provide 15 an automatic return of the plunger after the press stroke is finished.

Another object of the invention is to provide a device of this character which is simple and durable in construction, reliable 20 and efficient in operation and one which can be manufactured and placed upon the market at a minimum cost.

The invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is an elevation of the invention. Fig. 2 is a plan view thereof.

Fig. 3 is a horizontal section.

Fig. 4 is a section of the operating means on the line 4—4 of Fig. 2.

40 As shown in these views the invention comprises the press box 1 having the hopper 2 in its top and the bale box 3 extending from one end thereof. The top 4 of this bale box is flexibly connected with the press, and the upward movement of the rear end 45 thereof is controlled by the bar 5 under pressure of the springs 6. 7 represents the spring dogs preventing the re-bound of the binding block 8 on the return stroke of the plunger. 9 represents the plunger provided with the plunger rod 10.

50 11 represents the operating member which is pivotally mounted on the platform 12 by the bolt 13, said platform being carried by 55 the beams 14 forming extensions of the lower part of the press.

The operating member 11 is composed of an upper part 15 and a lower part 16 connected together by the diametrically arranged bolts 17 and sleeves 18 on said bolts 60 hold said parts in spaced relation. As will be seen the bolts 17 and the main bolt 13 are in the same vertical plane. Each of the parts 15 and 16 is provided with a cam or race-way 19 which consists of two substantially parallel parts connected together at the ends by the curved parts. A pin 20 on the plunger rod 10 engages said cams and said plunger rod is provided with a dog 21 which is adapted to engage with the sleeve 70 18 when the operating member 11 is rotated so that the plunger rod is moved forward to carry the plunger head into pressing action.

As will be seen the dog is slightly in advance of the pin 20 so that when the dog is 75 engaged the rearmost sleeve at the beginning of a pressing stroke the pin will be at the beginning of the curved parts of the cams. Thus when the operating member is moved the dog will pivot on the sleeve and 80 the pin will be engaged by the curved part of the cams, so that said pin will pass from one side of the cam to the other in a half revolution of the operating member. On the continual rotation of said member the 85 extreme end of the plunger rod will be pressed outwardly by the other sleeve, while the first sleeve will pass from the dog so that the spring 22, connecting said plunger rod with the platform, will cause said rod to 90 spring back into normal position with the dog engaging the other sleeve. In this operation the pin 20 passes along the parallel parts of the cams. It will thus be seen that a quick return of the plunger is secured. 95

While the operating device may be rotated by any suitable means I show a sweep 23 secured to the top part of the operating member by the bolts 13 and 24, said sweep being braced by the beams 25 engaged by 100 the bolts 17.

What I claim is:—

1. A baling press comprising a press box, a plunger operating in said box, a plunger rod, an operating member comprising a pair 105 of cam parts, a pin on the plunger rod engaging said cams and a dog on said rod engaging with a part of the operating member for moving the plunger forward and spring means for returning the plunger to 110 normal position.

2. A baling press comprising a press box,

a plunger operating therein, a plunger rod, an operating member comprising upper and lower portions, each having a cam groove therein, a centrally arranged bolt on which 5 said member is pivoted, diametrically arranged bolts connecting the two parts together, sleeves on said bolts spacing said parts apart, a pin on the plunger rod en-

gaging said cam grooves, a dog on said rod adapted to be engaged by the sleeves for 10 moving the plunger into pressing action and a spring for returning the plunger to normal position.

In testimony whereof I affix my signature.

JOHN F. WHITE.

Copies of this patent may be obtained for five cents each, by addressing the "Commissioner of Patents, Washington, D. C."
